(57) **CLAIM**

The ornamental design for a sprayer of a dish washing
machine, as shown and described.

DESCRIPTION

FIG. 1 is a perspective view of an embodiment of a sprayer
showing our new design;

FIG. 2 is a front view of the sprayer from FIG. 1, the rear
view being a mirror image thereof;

FIG. 3 is a right side view of the sprayer from FIG. 1, the
left side view being a mirror image thereof; and,

FIG. 4 is a top view of the sprayer from FIG. 1.

As shown in FIGS. 1-4, the sprayer has arms with a
reflective appearance as represented by the oblique line
shading. The broken lines show portions of the sprayer
for dish washing machine that form no part of the claimed
design.
